United States Patent Office.

THOMAS C. JENKS, OF PHILADELPHIA, PENNSYLVANIA.

Letters Patent No. 91,540, dated June 22, 1869.

**IMPROVED RAISED-LETTERED SIGNS, SHOW-CARDS, AND THE LIKE ARTICLES, FROM
PAPIER-MACHE.**

The Schedule referred to in these Letters Patent and making part of the same.

To all whom it may concern:

Be it known that I, THOMAS C. JENKS, of Philadelphia, Pennsylvania, have invented a new and improved Article of Manufacture from *Papier-Maché*; and I do hereby declare the following to be a full and exact description of the same.

My invention consists in the manufacture of raised-lettered signs or show-cards; and also letters to be affixed to wooden or other ground for signs, from *papier-maché*; by which means I form a complete sign or show-card from the *papier-maché*, by the use of suitable stamps, moulds, or presses, having the letters or figures and frame around said card or sign raised upon it, said letters or figures and frame being of one piece with the ground of the sign or card, and merely raised above the surface.

The letters for signs may be manufactured with steel dies, moulds, or tools.

To enable others skilled in the art to make and use my invention, I will describe more particularly the mode of operation.

I take a flat sheet of the *papier-maché*, in its wet state, and by the use of a mould or die, press up or stamp the frame and raised letters or figures upon the sign or card. It is then taken from the mould and submitted to any suitable drying process, after which it is dipped in linseed-oil, as is usual with articles made from this substance.

The sign or card, when dry, will then be ready to receive gilt or any color desired.

I cut the flat letters for signs from flat dry sheets of the *maché* by dies or stamps, and afterwards dip them in the linseed-oil, and dry for use, or they may be moulded from the wet *maché*.

The block letters are moulded or pressed from the *papier-maché* in its wet state, and dried and dipped in the linseed-oil, then again dried, when they are ready for use.

These letters, either flat or block, are to be secured to wood, glass, or other ground or backing, by screws, nails, hooks, or cement, to suit the material of which said ground or backing is composed.

Having thus described my improvements,

What I claim as new, and desire to secure by Letters Patent, as a new article of manufacture, is—

1. The manufacture of either block or flat letters or figures from *papier-maché*, substantially as described.
2. The manufacture of a complete sign or show-card, with raised letters or figures, with or without frame, said letters or figures, frame, and ground, being of one and the same piece, made of *papier-maché*, substantially as described.

3. Stamping a frame around the edge of the *papier-maché* show-card, of one and the same piece with the letters or figures and ground, substantially as described.

THOS. C. JENKS.

Witnesses:

GEORGE E. BUCKLEY,
W. A. A. MCKINLEY.
